UNITED STATES PATENT OFFICE.

JOHN B. HADAWAY, OF SWAMPSOFT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

TACK-PULLING MACHINE.

1,276,057.

Specification of Letters Patent. Patented Aug. 20, 1918.

Application filed April 5, 1916. Serial No. 89,156.

To all whom it may concern:

Be it known that I, JOHN B. HADAWAY, a citizen of the United States, residing at Swampscott, in the county of Essex and 5 State of Massachusetts, have invented certain new and useful Improvements in Tack-Pulling Machines; and I do hereby declare the following to be a full, clear, and exact 10 description of the invention, such as will enable others skilled in the art to which it appertains to make and use the same.

The present invention relates to tack pulling machines and more particularly to machines for removing side tacks from lasted 15 boots or shoes.

The object of the present invention is to provide an improved form of tack pulling machine having a simple and compact construction and which engages and removes 20 side tacks with certainty and rapidity.

With this object in view a feature of the invention consists in the combination of a pair of levers, a tack pulling jaw secured to the end of each lever, a rocker arm supporting both levers between their ends, a continuously rotated shaft, and connections between the shaft and opposite ends of the levers for oscillating the rocker arm to move the jaws forward and from a shoe and for 25 oscillating the levers about the rocker arm to move the jaws toward and from one another.

Further features of the invention consist in certain novel features of construction, 30 combinations and arrangements of parts hereinafter described and claimed, the advantages of which will be obvious to those skilled in the art from the following description.

40 In the accompanying drawings illustrating the preferred form of the invention; Figure 1 represents a side elevation of the improved tack pulling machine with the upper guard inclosing the tack pulling jaws removed; Fig. 2 is a top plan view of the mechanism shown in Fig. 1; Fig. 3 represents a side elevation of the tack pulling machine as a whole with the inclosing guards in place; and Fig. 4 is a detail upon 45 an enlarged scale illustrating the tack pulling jaws and coöperating work supports.

In the present invention two coöperating tack pulling jaws are mounted upon the ends of a pair of levers fulcrumed between their

ends upon a rocker arm. The levers are 55 actuated to impart the proper movements to the jaws by mechanism connected with the opposite ends of the levers and arranged to oscillate the rocker arm to move the levers in a lengthwise direction and to oscillate the 60 levers about the rocker arm to move the jaws toward and from one another. In order to cause the two jaws to move in paths of different lengths the levers are supported upon the rocker arm at different distances from 65 the center of oscillation of the arm. In the simplest and most efficient form of the invention which has yet been devised one of the jaw supporting levers is fulcrumed upon the eccentric head secured to the end of a 70 rock shaft, and the second lever is fulcrumed upon a crank arm located at one side of the eccentric head. The arrangement of the eccentric head and crank arm is such that the centers about which the levers fulcrum 75 75 are permanently in alinement so that this construction forms a practical embodiment of a single rocker arm for supporting the levers.

The tack pulling machine shown in the illustrated embodiment of the invention comprises coöperating tack pulling jaws indicated at 1 and 2 which are mounted upon the outer ends of supporting levers 4 and 5, 80 respectively. The jaw carrying levers are supported between their ends by a rock shaft 7 journaled in a transverse bearing formed in the machine frame, as shown clearly in Fig. 2. The jaw carrying lever 5 is fulcrumed upon an eccentric head 8 formed integrally with the shaft 7 and the jaw carrying lever 4 is fulcrumed at one side of the lever 5 upon a crank pin 9 secured to a crank arm 10 formed integrally with the face of 85 the eccentric head 8, as shown in Fig. 2. It will be obvious to those skilled in the art that this construction is the equivalent of a single crank with the levers fulcrumed thereon at different distances from the axis of 90 the shaft 7 forming effective crank arms of different lengths. Owing to the fact that the lever carrying the upper jaw 1, as shown clearly in Fig. 4, is supported upon a crank arm of greater length than the lever carrying the lower jaw 2, the extent of movement of the upper jaw toward and from the shoe 95 is greater than the extent of movement of 100 105

the lower jaw, causing the jaws to move in paths, as shown in Fig. 4. The shaft 7 is retained in position after the levers are assembled thereon by a collar 12 clamped to the opposite end of the shaft, as shown clearly in Fig. 2. The crank arm 10 serves to retain the lever 5 in position upon the eccentric 8 and the lever 4 is retained in position upon the crank pin 9 by a disk 13 and 10 stud 14, secured to the crank pin.

In addition to a bodily movement of the jaws toward and from the shoe the jaw carrying levers are also oscillated about the fulcra to move the jaws toward and from one another. The lever 4 is connected at its rear end to a crank 15 of suitable length secured to one end of a continuously rotating drive shaft 16. The driving crank 15 serves the dual function of oscillating the lever 4 to move the jaw 1 toward and from the jaw 2 and of rocking the shaft 7 to impart a bodily in and out movement of both jaws with relation to the shoe. The lever 5 carrying the jaw 2 is oscillated by a rotary cam secured to the shaft 16 and provided with two peripheral cam surfaces 17 and 18 which are engaged respectively by the parallel guide faces 19 and 20 formed upon the bifurcated end of the lever 5. This construction forms a simple and efficient mechanism for imparting the proper oscillatory movements to the lever 5 while permitting lengthwise movements of the lever relative to the cam. A tack receiving chute is located beneath the jaws and it is desirable to release the tack and merely drop it into the receiving chute rather than to forcibly eject the tack from between the jaws. To this end the jaws are actuated in such a manner that the paths separate slightly after the tack has been engaged and substantially removed from the shoe and prior to the relative movement of the jaws to eject the tack. This releases the tack and permits it to be easily disengaged when the upper jaw is moved beyond the lower jaw. The paths in which the two jaws move are clearly shown in Fig. 4 and the separation of the jaws is conveniently accomplished in the present construction by imparting a slight oscillatory movement to the lever 5 through the rotary actuating cam prior to the complete separation of the jaws. Each jaw has provision for adjustment in two directions with relation to the respective jaw carrying lever and to this end the jaw 1 is connected to the ends of the lever 4 through bolt and slot connections 21 and 22 and the jaw 2 is connected to the lever 5 through bolt and slot connections 23 and 24.

It is customary in this type of machine to provide coöperating work supports which engage with the lasted shoe upon opposite sides of the tack to be removed and with a fixed abutment extending transversely of

the line of tacks and arranged to position the tacks substantially in the plane of the tack pulling movement. To this end the present machine comprises a work support 26 connected to the under side of the tack receiving chute and arranged to engage with the lasted upper outside of the line of tacks. In addition, a work support 28 engages with the shoe inside of the line of tacks and the two work supports 26 and 28 form a throat in the usual manner for guiding the tacks to the tack pulling jaws. The tack is positioned in the plane of the tack pulling movement by an abutment 27 extending transversely of the line of tacks in the usual manner. It is desirable that the work support 28 shall be positioned in close proximity to the path of movement of the tack pulling jaws and in order to avoid injury to the machine if a jaw accidentally contacts with the work support 85 the latter is arranged to yield outwardly away from the path of movement of the jaws. To this end the work support 28 is secured to a curved arm 30 pivoted upon the frame at 31 and extending outwardly and downwardly from the fulcrum, as shown clearly in Fig. 4. The arm 30 is fulcrumed upon a head 32 having a face 33 which engages with the under side of the arm to limit the downward movement. The arm is normally depressed by a coil spring 35 surrounding a stud 36 upon which the arm is pivoted and connected at its opposite end to a pin 37 extending from the head 32, as shown clearly in Fig. 2. The work support 100 is adjustably connected to the lower end of the arm through a bolt and slot connection indicated at 40. This construction permits the work support to move outwardly away from the path of movement of the jaws and 105 at the same time owing to the location of the fulcrum, imparts an upward movement to the work support. This feature is of decided advantage as the operator is enabled to vary the position of the work support by 110 the upward pressure of the shoe. This movement of the work support simultaneously widens the tack guiding throat and permits the movement of the shoe bottom toward the path of movement of the tack 115 pulling jaws, the shoe pivoting about the outer work support 26 as the work support 28 is moved outwardly and upwardly.

While it is preferred to employ the specific construction and arrangement of parts shown and described, it will be understood that this construction and arrangement is not essential except so far as specified in the claims, and may be changed or modified without departing from the broader features 125 of the invention.

The invention having been described, what is claimed is:

1. A tack pulling machine, having in combination, a pair of levers, a tack pulling jaw 130

- secured to the end of each lever, a rocker arm supporting both levers between their ends, a continuously rotated shaft, and connections between the shaft and the opposite 5 ends of the levers for oscillating the rocker arm to move the jaws toward and from a shoe and for oscillating the levers about the rocker arm to move the jaws toward and from one another.
- 10 2. A tack pulling machine, having in combination, coöperating tack pulling jaws, a lever supporting each jaw, a rock shaft, a rocker arm projecting from the shaft and supporting the levers between their ends at 15 different distances from the axis of the shaft, and mechanism for oscillating the levers about the rocker arm.
3. A tack pulling machine, having in combination, a pair of coöperating tack pulling 20 jaws, a lever supporting each jaw, a rock shaft, a rocker arm projecting from the shaft and supporting the levers between the ends, a driving crank operatively connected to the end of one of the levers, and a rotary cam 25 operatively connected to the end of the second lever.
4. A tack pulling machine, having in combination, a pair of levers, a tack pulling jaw secured to the end of each lever, a rocker 30 arm supporting both levers between their ends, and mechanism for actuating the rocker arm to move the jaws toward and from a shoe and for oscillating the levers about the rocker arm to open and close the 35 jaws.
5. A tack pulling machine, having in combination, a pair of levers, a tack pulling jaw secured to the end of each lever, a rocker arm supporting both levers between their 40 ends, a driving crank connected to the opposite end of one of the levers for oscillating the lever about the rocker arm and for moving the lever in a lengthwise direction, and a rotary cam operatively connected to the 45 second lever for oscillating the lever.
6. A tack pulling machine, having in combination, a pair of coöperating tack pulling jaws, and actuating mechanism constructed and arranged to first impart a movement of 50 separation to the jaws during the tack pulling movement sufficient to relieve the pressure upon the tack and to next move the 55 jaws relative to one another in the direction of the tack pulling movement after the pressure upon the tack has been relieved to disengage the tack from between the jaws.
7. A tack pulling machine, comprising, a tack pulling jaw, mechanism for actuating the jaw, a work support engaging with the upper of the shoe outside of the line of tacks, a second work support engaging with the shoe inside of the line of tacks, and means for permitting the second support to yield laterally away from the path of the tack pulling jaw. 60
8. A tack pulling machine, comprising, a tack pulling jaw, mechanism for actuating the jaw to engage and pull a tack, coöperating work supports engaging upon opposite sides of the line of tacks, a fixed abutment 65 extending transversely of the line of tacks, and mechanism for permitting one of the work supports to yield upwardly.
9. A tack pulling machine, comprising, a tack pulling jaw, mechanism for actuating the jaw to engage and pull a tack, and coöperating work supports engaging with the shoe upon opposite sides of the line of last- 70 ing tacks, one of the supports having provision for a yielding movement to simultaneously move the support upwardly and away from the path of the tack pulling jaw.
10. A tack pulling machine, comprising a rock shaft, an eccentric and a crank arm each secured to the rock shaft, a pair of 75 levers fulcrumed respectively upon the eccentric and crank arm, a tack pulling jaw secured to the end of each lever, and mechanism for actuating the rock shaft and for oscillating the levers about the fulcrums to 80 move the jaws bodily toward and from a shoe and toward and from one another.
11. A tack pulling machine, having in combination, a pair of coöperating tack pulling 85 jaws, and actuating mechanism constructed and arranged to first move the jaws to grip and pull the tack, to next move the jaws to relieve the pressure upon the tack, and to finally move the jaws to discharge the tack whereby the tack discharging move- 90 ment of the jaws takes place after the pressure upon the tack has been relieved.
- 100
